UNITED STATES PATENT OFFICE.

CHARLES W. BIRKIN, OF NOTTINGHAM, ENGLAND.

DESIGN FOR LEVERS LACE.

No. 37,839.

Specification for Design.

Patented Feb. 20, 1906.

Application filed January 12, 1906. Serial No. 295,824. Term of patent 3½ years.

To all whom it may concern:

Be it known that I, CHARLES W. BIRKIN, a subject of the King of Great Britain and Ireland, residing at Nottingham, county of Nottingham, England, have invented a new, original, and ornamental Design for Levers Lace, of which the following is a specification, reference being had to the accompanying drawing, forming a part thereof.

The figure is a plan view of a section of Levers lace, showing my design.

I claim—

The ornamental design for Levers lace as shown.

CHAS. W. BIRKIN.
